(57) CLAIM

I claim the ornamental design for a scarecrow stake, as shown and described.

DESCRIPTION

FIG. 1 is a perspective view of a scarecrow stake;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view of a scarecrow stake.

The broken lines form no part of the claimed design.
